UNITED STATES PATENT OFFICE.

HERBERT L. AMENT, OF CHICAGO, ILLINOIS, ASSIGNOR TO HENRY JANSEN, OF CHICAGO, ILLINOIS.

DISPLAY-HOOK.

1,181,102.

Specification of Letters Patent.

Patented May 2, 1916.

Application filed September 4, 1913. Serial No. 788,073.

To all whom it may concern:

Be it known that I, HERBERT L. AMENT, a citizen of the United States, residing at Chicago, in the county of Cook and State of Illinois, have invented a certain new and useful Improvement in Display-Hooks, of which the following is a full, clear, concise, and exact description, reference being had to the accompanying drawings, forming a part of this specification.

My invention relates to display hooks, and especially to a type of display hook adapted for displaying various articles in windows or other places, and also supporting a tag or card indicating price or other information about the article.

Prominent objects of the invention are to provide a simple, practical and efficient form of hook of the class specified; to cheapen and simplify the same and reduce the cost of manufacture; to insure effectiveness of operation, durability and efficiency; and to secure the foregoing and other desirable results in a simple and expeditious manner.

In the accompanying drawings, Figure 1 is an elevational view of a display hook embodying my invention; Fig. 2 shows the strips or blanks from which the same may be made; Fig. 3 is a side view of the hook; Fig. 4 is a view similar to Fig. 1 of a modification; Fig. 5 is a view similar to Fig. 2 of the blanks from which the hook of Fig. 4 may be made, and Fig. 6 is a view similar to Fig. 3 of the device of Figs. 4 and 5.

The hook embodying my invention involves a hook portion by which it may be suspended, a spring jaw arrangement by which the article can be positively clasped or caught, and also preferably involves means by which a card or tag supplying desired information may be supported near the article. To such end, as I prefer to make it, it comprises two separable parts which may be engaged with one another, and so constructed as to maintain such engagement and provide the desired portions above mentioned. These separable parts are conveniently in the form of metal strips or blanks, cut or formed in certain shape. In Figs. 1, 2 and 3, I have shown such blanks 1 and 2, which may be made of steel or other suitable strong and springlike material.

The blank 1 is shown formed with an

upper narrow straight portion 1^a, and a lower wider portion 1^b, which latter is provided with a slot or opening 3, and is cut at 4, 4 to form side strips or tongues 5, 5. The blank 2 is formed with a narrow lower end 6 and a widening or tapering upper portion 7 having an aperture 8. The portion 6 of the blank 2 may pass into and move within the slot 3 of the blank 1; and the end portion 1^a of the blank 1 may enter the opening 8 in the blank 2. The two blanks are bent and are then fastened together, as shown in Figs. 1 and 3. As shown in these figures, the upper end of portion 1^a is inserted in aperture 8, and the lower portion 6 of blank 2 is passed through slot 3, and lower ends of 1^b and 6 bent laterally to form coöperating jaws 9 and 10, respectively. The blanks are also bent so that the upper portions thereof form a hook portion by which the device may be supported or hung upon a rod or other object. The blanks are further bent at 11 and 12 to form the portions which extend angularly and cross one another. The side strips 5, 5 are bent outwardly a little to form holders for engaging a card. Thus the completed device may be supported from a rod or otherwise and the members 1 and 2 may be pressed toward one another (Fig. 3), so as to separate the spring jaws 9 and 10. The article to be supported may then be inserted between the jaws and then the same be permitted to spring close or as nearly close as they can, with said article between them; it being observed that the portion 1^a of the blank or member 1 is bent with less curvature than portion 7 of blank 2, so that blank 1 tends more strongly to straighten out, thereby tending to hold the jaws 9 and 10 normally closed.

In the arrangement shown in Figs. 4, 5 and 6, the hook is made up very much as shown in the preceding figures, but there is what may be said to be a reversal of the arrangement of the two blanks. Thus a blank 1^c is provided with downwardly extending tongues 5^a, 5^a, which are bent up as shown in Fig. 6, to form the clips for engaging the card; and the other blank 2^c is provided with an aperture 15, through which the lower end 16 of the blank 1^c may pass, said end 16 being bent so as to extend through said aperture and being also bent to form a jaw 10^a. The blank 2^c is also provided with 110

an aperture 8^a. Thus referring to Figs. 3 and 6, in the modification of Fig. 6 the left hand member 1^c passes through an aperture in the right hand member 2^c, which is just 5 the reverse of the arrangement of Fig. 3. In other ways, however, the construction and operation of the hook is substantially the same.

It will be understood that I do not wish 10 to limit myself to the making of the hook out of two blanks as shown, nor to other specific features of construction, for it can readily be seen that changes and modifications may be made, without departing from the 15 spirit of the invention.

What I claim is:

1. A device of the class described composed of two separable members having their upper ends provided with interlocked 20 spring end portions bent to form a hook, said members tending to spring away from one another and having their lower ends crossed and provided with inturned ends to form jaws normally held in engagement 25 by the tendency of said members to spring apart.

2. A device of the class specified composed of two separable members having their upper ends interlocked and bent to 30 form a hook portion, said ends forming springs, the ends of said members remote from the bent ends being provided with jaws normally held in engagement by said 35 spring ends, the lower portion of one of said separable members being apertured and the end of the other of said members passing through the aperture in said member.

3. A device of the class described comprising two separable members having their upper 40 ends interlocked and bent to form a hook

portion, the ends of said members remote from the hooked ends being crossed and provided with coöperating jaws, one of said members being apertured at its end to receive the end of the other member, the hook 45 portion of said members forming springs, and one of said members being positioned within the hooked portion of the other member.

4. A device of the class described comprising two separable members one mounted within the other, each of said members being provided at its opposite ends with a spring end and one part of a coöperating jaw, the ends of said members remote from 50 said spring ends being normally held together by the spring ends of said members.

5. A device of the class described comprising two separable members, each one of which is apertured at its end to receive the 60 end of the other, the opposite ends of each member being provided with a spring end and a clamping jaw, said jaws being normally held together by the spring ends of 65 said members.

6. A device of the class described comprising two separable members, one mounted within the other, each of said members being apertured to receive the end of the other, the opposite end of each member being provided with a spring end and a clamping jaw, said jaws being normally held together by the spring ends of 70 said members.

In witness whereof, I hereunto subscribe my name this 6th day of June, A. D. 1913 75

HERBERT L. AMENT.
